UNITED STATES PATENT OFFICE

119,081

DESIGN FOR A COOKING UTENSIL FOR
EGGS, HAMBURGER, PANCAKES, SAND-WICHES OR THE LIKE

Thomas Weststrang, Chicago, Ill.

Application November 13, 1939, Serial No. 88,233

Term of patent 14 years

To all whom it may concern:

Be it known that I, Thomas Weststrang, a citizen of the United States, residing at Chicago, in the county of Cook and State of Illinois, have invented a new, original, and ornamental Design for a Cooking Utensil for Eggs, Hamburger, Pancakes, Sandwiches or the like, of which the following is a specification, reference being had to the accompanying drawing, forming part thereof.

utensil, for eggs, hamburger, pancakes, sandwiches or the like, showing my new design.

I claim:

The ornamental design for a cooking utensil, for eggs, hamburger, pancakes, sandwiches or the like, as shown.

THOMAS WESTSTRANG.
